(57) **CLAIM**

The ornamental design for a display screen or portion thereof with animated graphical user interface, as shown and described.

DESCRIPTION

FIG. 1 shows a first image in a sequence for a display screen or portion thereof with animated graphical user interface showing my new design;

FIG. 2 shows a second image thereof;

FIG. 3 shows a third image thereof;

FIG. 4 shows a fourth image thereof;

FIG. 5 shows a fifth image thereof;

FIG. 6 shows a sixth image thereof;

FIG. 7 shows a seventh image thereof;

FIG. 8 shows a first image in an alternative sequence for a display screen or portion thereof with animated graphical user interface showing my new design;

FIG. 9 shows a second image thereof;

FIG. 10 shows a third image thereof;

FIG. 11 shows a fourth image thereof;

FIG. 12 shows a fifth image thereof;

FIG. 13 shows a sixth image thereof; and,

FIG. 14 shows a seventh image thereof.

The appearance of the animated user interface sequentially transitions between the images shown in FIGS. 1-7 or FIGS. 8-14. The process or period in which one image transitions to another image forms no part of the claimed design.

The broken lines showing an electronic device and a display screen are included for the purpose of illustrating environmental subject matter and form no part of the claimed design.
